UNITED STATES PATENT OFFICE.

THOMAS L. STURTEVANT, OF QUINCY, MASSACHUSETTS, ASSIGNOR TO STURTEVANT MILL COMPANY, OF BOSTON, MASSACHUSETTS, A CORPORATION OF MASSACHUSETTS.

SEPARATOR.

1,353,546.

Specification of Letters Patent. Patented Sept. 21, 1920.

Application filed September 21, 1917. Serial No. 192,478.

To all whom it may concern:

Be it known that I, THOMAS L. STURTEVANT, a citizen of the United States, residing at Quincy, county of Norfolk, and State of

5 Massachusetts, have invented an Improvement in Separators, of which the following description, in connection with the accompanying drawings, is a specification, like characters on the drawings representing like 10 parts.

The invention hereinafter described relates to separators for grading materials, and more particularly to devices for vibrating the screen of the separator.

15 Such separators usually comprise an inclined casing having a feed box at the top thereof containing a conveyer screw which feeds the material to be graded along the feed box over a feed board into the screen

20 casing. The material flows along the upper surface of the screen, and the fines are delivered through one outlet and the tailings are delivered through another outlet at the bottom of the casing.

25 In order to efficiently grade the material, it is necessary to vibrate the screen sufficiently to cause the material to pass readily through the screen without throwing the material too high above the screen to prevent the grading of the maximum amount of 30 the material as it flows along the screen.

35 One of the objects of the invention is to provide a simple and effective device for imparting the desired character of vibration to the screen.

Another object of the invention is to provide a device for vibrating the screen which may be carried entirely by the cover of the casing and be lifted upward therewith when 40 it is desired to have access to the screen for the purpose of inspection, removal or repair thereof.

Another object is to provide a device for vibrating the screen comprising a spring member combined with a pin adapted to project through the casing toward and to strike the screen.

And still another object of the invention is to provide a device for vibrating the screen 50 which is simple and cheap to manufacture, and durable and efficient in operation.

The character of the invention may be best understood by reference to the following description of one good form thereof shown in the accompanying drawing, wherein:

55 Figure 1 is a vertical section through a separator equipped with a screen vibrating device embodying the invention;

Figure 2 is a transverse section taken on line 2—2 of Fig. 1; and

60 Figure 3 on an enlarged scale is a detail view showing parts of the screen vibrating device.

Referring to the drawing, the separator shown therein as an exemplification of the 65 invention comprises a frame 1 having an inclined casing mounted thereon comprising a bottom 3, side walls 5 and a cover 7, having its upper end connected by a hinge 9 with the casing and its lower end adapted to 70 rest upon a transverse member 11 adjacent the lower end of the casing.

One or more screens may be mounted in 75 this casing, in the present instance of the invention, a single screen being shown, comprising screen clothing 13 stretched upon a frame consisting of longitudinal side bars 15 and transverse end bars 17. The screen frame may be suitably supported in the casing to permit the vibration thereof. In the 80 present instance of the invention, the side bars of the screen frame are mounted on the upper curved ends of leaf springs 19 having their lower ends secured to bars 21 mounted on the bottom of the casing adjacent the 85 sides thereof. Downward movement of the springs may be limited by stops 23 mounted on said side bars beneath the upper curved ends of said leaf springs.

The screen is made somewhat narrower 90 than the width of the casing, in order that it may be inserted into and removed from the casing without interference from the angle bars at the tops of the sides of the casing. To prevent escape of the material 95 over the side edges of the screen, shield plates 24 may depend from the cover and overlap similar plates 25 secured to and rising from the side bars of the screen frame.

100 Next will be described the means for vibrating the screen. In the present instance

of the invention, this means comprises a spring member 26 having a part 27 secured in fixed position on a bracket 29 having feet secured to the casing cover. A pin 5 31 is carried by the resilient member and projects down through the cover toward the screen. In the present instance of the invention, the spring member and pin are formed of one integral ribbon of tempered 10 steel or other suitable material, bent so that the spring member extends substantially parallel to the cover of the casing, and the pin projects transversely to said member perpendicularly to the cover of the casing.

15 Preferably, the bend in the ribbon is given a gradual curve 33 to add to the strength of the bend and contribute to the resilience thereof. The ribbon may also be given a bend 35 with a gradual curve further to contribute to the strength and resilience thereof. The lower end of the pin 20 may strike any suitable part of the screen, such as its clothing, frame, or protective armor, or a member connected to the screen. 25 In the present instance, the pin is adapted to strike the bottom of a guard 37 mounted on the clothing above a transverse bar 39 connected to the side bars of the screen frame. This guard has a deflector 37^a which 30 serves to divert the material from the point of intermittent engagement of the pin with the guard. To prevent objectionable wear on the screen part engaged by the pin, the lower end of the latter may be curved to 35 present a foot 40 having a substantial bearing surface.

To facilitate the mounting of the combined spring member and pin in its operative position on the cover and to facilitate 40 removal therefrom, the pin may project through an opening 41 (Fig. 3) in the cover sufficiently large to permit the foot 40 to pass therethrough. A cap plate 43 for this opening may be secured by bolts to the cover, and have a hole therein to receive the pin.

50 Suitable means is provided for energizing or flexing the spring member to cause the pin carried thereby to strike and vibrate the screen. In the present instance of the invention, this means comprises hammers or strikers 45 pivotally connected to arms 47 projecting from a split hub 49 fast on a shaft 51 journaled in bearings in brackets 55 53 secured to the top of the casing cover. The shaft may be rotated by any suitable means, unnecessary to show herein.

60 The construction is such, that as the shaft is rotated, the hammers fly around and strike successive blows adjacent the bend 33 of the strip. This flexes the spring member and causes the same to vibrate the pin 31, which, in turn transmits the vibrations to the screen. The foot of the pin 31 preferably normally is out of engagement with

the screen, but when the spring member is vibrated, it moves down into engagement with the screen and may impart blows thereto with a force diminishing as the amplitude of vibration of the spring member 70 diminishes.

Since the pin is carried by the spring member, the screen is relieved from the weight and deadening effect of the pin thereon, thereby permitting a greater freedom 75 of vibration of the screen than if it had to support the weight of a pin, which obviously would tend to diminish the screen vibration.

The pin delivers an instant blow to the 80 screen and recoils immediately therefrom, in a manner somewhat similar to the action of a piano hammer in its tap on and recoil from a piano wire.

In a sense the spring member and the pin 85 constitute a recoiling spring hammer for vibrating the screen, and the rotating strikers serve as the actuating means for setting the spring hammer in motion.

The present form of spring hammer 90 means shown, has a high degree of liveliness due to the resilience of the member 26, pin 31, curved bends 33 and 35, and the curved foot 37 thereof.

The spring member and pin may be ad- 95 justably mounted. In the present instance, to accomplish this, one or more shims 55 may be interposed between the top of the bracket and the fixed part 27 of the spring member and may be secured by bolts 57 en- 100 tered therethrough.

This adjustment will permit the distance of the foot of the pin from the screen to be varied, and if desired the distance may be such that the pin will strike the screen with 105 but a single tap for each blow of the rotating hammers. Also this adjustment will permit the end of the spring member struck by the hammers to be raised or lowered relatively to the axis of rotation of the latter to 110 vary the force of the blows of the hammers on said member. Screens of different character and tension will vibrate differently, but this adjustment will permit the vibrations of the spring member to be timed and 115 regulated to conform to different screens and conditions as desired.

The screen vibrating device described may constitute one of several similar units, the number of which will vary according to the 120 size of the screen and conditions as required. In the present instance of the invention, four such units are used, two on each of a pair of shafts mounted on the cover.

While the screen vibrating device has been 125 shown as mounted on the cover, it will be understood that it may be located in a different position if desired.

It will be understood that the invention is not limited to the specific embodiment 130

shown, but that various deviations may be made therefrom without departing from the spirit and scope of the appended claims.

What is claimed is:—

- 5 1. In a separator, the combination of a casing, a screen for grading materials mounted in said casing, and means for vibrating said screen comprising a bracket mounted on said casing, a resilient arm having one end secured to said bracket and a portion extending a substantial distance from said bracket along said casing, and a portion extending thence transversely to said first named portion through the casing 15 and having an end for engagement with the screen, and rotary swing hammer means mounted on said casing for imparting blows to said arm at the juncture of said transverse portions.
- 20 2. In a separator, the combination of a casing, a screen for grading materials mounted in said casing, and means for vibrating said screen comprising a bracket mounted on said casing, a resilient member having a part adjustably secured to said bracket that the distance of said member from the screen may be varied, a striker member connected to said resilient member and projecting transversely thereto through 25 the casing toward said screen, and rotary swing hammer means for imparting blows to said members at the juncture of said members.
- 30 3. In a separator, the combination of a casing, a screen for grading materials mounted in said casing, and means for vibrating the screen comprising a bracket mounted on said casing, a resilient ribbon member having a part secured to said 35 bracket, a ribbon striker member connected to said resilient member and projecting transversely thereto through an opening in the casing toward the screen and having a rounded end to act on the screen, rotary 40
- means for intermittently engaging said resilient member to cause the striker member to act on the screen, said casing opening being sufficiently large to allow the rounded end of said striker member to pass therethrough, and a cover plate fitting said 45 striker plate for closing the opening in said casing.
4. In a separator, the combination of a casing, a screen for grading materials mounted in said casing, and means for vibrating said screen including a resilient member bent to present a portion extending along the exterior of the casing, and a portion extending transversely to said first 50 named portion into the casing toward the 55 screen to strike the latter, a support for the portion of the resilient member at the exterior of the casing, and means for intermittently energizing said member.
5. In a separator, the combination of a 60 screen for grading materials, and means for vibrating said screen including a substantially L-shaped member having a vibratory resilient leg extending approximately parallel to the screen and an integral striker leg 65 projecting a substantial distance therefrom toward the screen, and rotary hammer 70 means for imparting blows to said members adjacent the juncture of said legs.
6. In a separator, the combination of a 75 screen for grading materials, and means for vibrating said screen including a support, a substantially L-shaped member having a resilient leg with an end thereof secured to said support and a striker leg projecting 80 from the opposite end of said leg toward the screen, and rotary hammer means for imparting blows to said member at the juncture of said legs.

In testimony whereof, I have signed my 85 name to this specification.

THOMAS L. STURTEVANT.
